UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

PERCUSSION TOOL.

Application filed April 7, 1919. Serial No. 288,187.

To all whom it may concern:

Be it known that I, CHARLES W. WYMAN, a citizen of the United States, residing at Claremont, in the county of Sullivan and State of New Hampshire, have invented certain new and useful Improvements in Percussion Tools, of which the following is a full, clear, and exact specification.

This invention relates to tools and especially to that type of tool wherein a bit is driven against the work by the impact of a force against the bit.

One object of the present invention is to provide an improved tool. Another object is to provide a simple, easily assembled tool having a minimum number of wearing parts, and a tool in which the force of the blow is delivered instantaneously to the bit. These and other objects and advantages of my improved construction will, however, herein-after more fully appear.

In the accompanying drawings, I have shown for purposes of illustration two embodiments which my invention may assume in practice.

In these drawings,—

Fig. 1 is a side elevation partly in section of my improved tool.

Fig. 2 is a longitudinal sectional view 30 thereof taken substantially on the line 2—2 Fig. 1.

Fig. 3 is a side elevation of the cam.

Fig. 4 is a transverse sectional view on the line 4—4 Fig. 2.

Fig. 5 is a partial longitudinal sectional view illustrating a modified form of my invention.

In these drawings I have shown a casing or tube 1 provided adjacent one end thereof with guiding means herein shown as slots 2 formed in the casing, these guiding means being adapted to receive a cross head or transversely disposed section 3 of a spring 4 herein in the form of a spiral coil mounted 45 coaxially within the tube 1. A bit 5 having any suitable cutting edge 6 is herein shown as mounted on and guided by the tube or casing 1 by means of a head 7, preferably formed integral with the bit 5, this head 50 having a reduced portion 8 which may be inserted in the end of the casing. This bit is preferably held in operative position by a threaded projection 9 which is preferably threaded into one end of the coiled spring 4, 55 the latter retaining the bit in the casing

through its elasticity and through the contact of the cross head 3 in the end walls of the guiding slots 2.

Any suitable means may be used for elongating and releasing the spring but herein I have shown a sleeve or head 10 rotatably mounted on the rear end of casing 1 and having a handle 11 by means of which the head 10 is rotated to rotate a cam sleeve or bushing 12 which preferably has cam surfaces 13 adapted to engage the ends of the cross head 3 and a longitudinally disposed slot 14 which permits a free reciprocation of the cross head in the cam sleeve 12. This cam sleeve may be fastened to the head 10 by any means desired, but for convenience, I show it detachably secured thereto by screws 15, the latter facilitating the assembly of the parts.

If it is desired to add weight to the moving parts so as to increase the impact of the blow delivered to the bit, a head 16 having a cross pin 17 may be substituted for the cross head 3 and the spring 4 may be threaded onto a nipple 18 projecting from the forward end of the head 16 in a manner similar to the connection between the spring 4 and the nipple 9 of the bit 5.

In the operation of my improved tool, when the casing 1 is gripped in one hand or held against relative rotation by any other means desired, and the handle 11 is rotated to turn the cam sleeve 12, the inclined surfaces 13 will force the cross head 3 or 17 rearwardly until the cross head reaches the slot 14 when the spring will be free to contract and the coils of the springs will come together simultaneously so as to deliver the additive force of the successive coils simultaneously to the bit 5. The force of the blow delivered to the bit will be much greater than if the coils of the springs contacted successively so as to produce a blow operative over a short timed interval instead of an instantaneous blow.

It will be noted that this tool is composed of but a very few parts which are easily assembled, that wear is reduced to a minimum, that the cost of manufacture is very small, and that the part of the instrument which actuates the bit is also the part of the instrument which retains the bit in its proper position in the tube or casing. It will further be noted that if the bit is not held against the work when the blow is 110

delivered to the tool, that the spring will be elongated again as the tool is driven outward, but this elongation and the resultant tension of the spring will not be sufficient 5 to materially reduce the force of the blow.

While I have in this application specifically described two embodiments which my invention may assume in practice, it is to be understood that these forms are shown for 10 illustrative purposes only, and that the invention may be modified and embodied in various other forms without departing from its spirit or the scope of the appended claims.

15 What I claim as new and desire to secure by Letters Patent is:

1. In a tool, a bit, resilient actuating means for said bit operative to transmit thereto a blow whose force is derived from a 20 plurality of simultaneous blows, and cam means for alternately retracting and releasing said resilient means.

2. In a tool, a bit, resilient actuating means for the bit operative to transmit there- 25 to the force of a plurality of substantially simultaneous blows, and means operative both to effect retraction and release of the resilient means on unidirectional movement of said second mentioned means.

30 3. In a tool, a tool element, a stationary casing, resilient actuating means thereon comprising a spring coacting directly with said tool element, a cam cooperating with said resilient actuating means, and means 35 mounted on the exterior of said casing for operating said cam.

4. In a tool, a casing, a tool element carried thereby, and means for striking a blow

on said tool element having provision for retaining said element in operative position. 40

5. In a tool, a casing, a bit, and a resilient means for imparting a blow to said bit operatively connected with said bit and having means disposed at its end remote from said bit for retaining said bit in said casing. 45

6. In a tool, a casing, a bit guided and supported by said casing, a coiled spring attached to said bit for retaining the same in the casing, a cross head on the opposite end of the coiled spring, guiding means for said 50 cross head and means engaging said cross head to extend the coiled spring and release the latter at a predetermined instant.

7. In a tool, a casing, a bit guided and supported by said casing, a coiled spring attached to said bit for retaining the same in the casing, a cross head on the opposite end of the coiled spring, and a rotary member having a cam surface engageable with said cross head to extend the coiled spring and 55 release the latter at a predetermined instant.

8. In a tool, a casing, a bit guided and supported by said casing, a coiled spring attached to said bit for retaining the same in the casing, a cross head on the opposite end of the coiled spring, means cooperating therewith for limiting the movement thereof and means engaging said cross head to extend the coiled spring and release the latter at a predetermined instant, the coils of the 70 spring contacting with each other simultaneously to transmit the additive effect of the impact of the coils simultaneously to the bit when the spring is released.

In testimony whereof I affix my signature. 75

CHARLES W. WYMAN.
